UNITED STATES PATENT OFFICE.

FERRIS L. R. FRANCISCO, OF JERSEY CITY, NEW JERSEY.

HANGER.

972,525.

Specification of Letters Patent. Patented Oct. 11, 1910.

Application filed November 30, 1909. Serial No. 530,534.

To all whom it may concern:

Be it known that I, FERRIS L. R. FRANCISCO, a citizen of the United States, residing at Jersey City, in the county of Hudson 5 and State of New Jersey, have invented a new and useful Improvement in Hangers, of which the following is a specification.

This invention relates to an improvement in hangers, particularly to that type of 10 hangers used in connection with steel and concrete buildings.

In certain buildings, whether or not concrete is used in their construction, what is known as I-beams are extensively employed, 15 the beams being arranged to carry the load of the floors and a system of pipes or shafting. In suspending pipes, shafts or other devices from such beams, it has been customary heretofore to drill holes in the flanges 20 of the beams and bolt the devices thereto. This method of hanging the devices is expensive.

It is one of the objects of the present invention to provide a hanger adapted for 25 use in connection with I-beams which is secured to the beam without bolts or other fastenings apart from the hanger itself.

In buildings constructed of concrete, or steel and concrete, it has been customary to 30 employ inserts buried in the concrete to which hangers may be fastened. It is sometimes desirable to position hangers after a building has been completed.

It is a further object therefore to provide 35 a device that can be used both before and after a building has been completed.

Another object is to provide a hanger that may be cast and used without machining or hand fitting, thus reducing its cost. 40 With these and other objects not specifically mentioned in view, the invention consists in certain constructions and combinations which will be hereinafter fully described and then specifically pointed out in 45 the claims hereunto appended.

In the accompanying drawings which form a part of this specification and in which like characters of reference indicate the same parts, Figure 1 is a plan view of a 50 device constructed in accordance with the invention, Fig. 2 is an end view of the structure shown in Fig. 1, and Fig. 3 is a sectional view taken on the line 3—3 in Fig. 1 and showing the manner of applying the 55 device.

In carrying the invention into effect there

is provided a pair of jaws which may vary within wide limits, both in form and material. In the best constructions however and as shown, cast or malleable iron jaws 60 1 and 2 are employed, the outer ends of the jaws respectively terminating in hooks 3 and 4 adapted to engage the flange of an I-beam, as shown in Fig. 3.

In order to eliminate the necessity for 65 machining or drilling holes and fitting bolts to hold the hanger in position, interlocking means whereby the jaws are held is provided, and this means may vary within wide limits. As shown however, the interlocking 70 means consists in ribs 5 and 6 respectively integral with the jaws 1 and 2 and running transversely across the device. These ribs are tapered slightly at 13 and arranged to slide by each other when the 75 hanger is applied to the flange of an I-beam, and become interlocked by their wedging action.

For the purpose of supporting stringers or other devices suspended from the hanger, 80 one of the jaws is provided with a nut seat 7 sunk in the upper surface of the jaw and shaped to prevent the turning of a nut placed therein. An aperture 8 is provided in the bottom of the nut seat through which 85 a bolt may be passed to engage the nut on the seat, as shown in Fig. 3.

In the operation of the device, a nut 10 is dropped on the seat 7, and the jaw is placed in position under the flange of an I-beam 90 with its hooked end engaging the flange. The jaw 2 is then hooked over the opposite side of the flange and slid or driven into position, the ribs 5 and 6 serving to interlock the two jaws and flange. At any time 95 after the device is in position, a stringer 11 or other device, may be suspended from the hanger by a bolt 12 coöperating with the nut 10.

When the device is to be used in connection with a concrete building under construction, it is placed in position before the floors are formed, and may be used for the purpose of supporting the forms for said floors. Further, it may be buried in the concrete when the floor is completed with only the bolt hole visible. When the device is to be used in connection with a concrete building already completed, the concrete is chipped away from the I-beam where the hanger is to be applied, the device positioned, and new concrete filled in around it. 100 105 110

Changes and variations may be made in the structure by which the invention is carried into effect. The invention therefore is not to be restricted to the precise details of the structure shown and described.

5 What is claimed is:

1. In a hanger, the combination with a pair of jaws terminating in hooks adapted to engage the flange of an I-beam, of ribs 10 integral with the jaws and spaced from the hooks said ribs being shaped to lock the jaws together, substantially as described.
2. In a hanger, the combination with a pair of jaws terminating in hooks adapted 15 to engage the flange of an I-beam, of transverse tapered ribs integral with the jaws and spaced from the hooks said ribs being shaped to slide by each other into locking position, substantially as described.
- 20 3. In a hanger, the combination with a pair of jaws terminating in hooks adapted to engage the flange of an I-beam, one of

the jaws being provided with a nut seat and an aperture in the bottom of the seat, of ribs integral with the jaws and spaced from 25 the hooks said ribs being shaped to lock the jaws together, substantially as described.

4. In a hanger, the combination with a pair of jaws terminating in hooks adapted to engage the flange of an I-beam, one of the jaws being provided with a nut seat and an aperture in the bottom of the seat, of transverse tapered ribs integral with the jaws and spaced from the hooks said ribs being shaped to slide by each other into locking position, 30 substantially as described.

35 In testimony whereof, I have signed my name to this specification in the presence of two subscribing witnesses.

FERRIS L. R. FRANCISCO.
